T. H. SYMINGTON.

JOURNAL BOX.

APPLICATION FILED FEB. 6, 1908.

904,460.

Patented Nov. 17, 1908.

UNITED STATES PATENT OFFICE.

THOMAS H. SYMINGTON, OF BALTIMORE, MARYLAND, ASSIGNOR TO THE T. H. SYMINGTON COMPANY, OF BALTIMORE, MARYLAND, A CORPORATION OF MAINE.

JOURNAL-BOX.

No. 904,460.

Specification of Letters Patent.

Patented Nov. 17, 1908.

Application filed February 6, 1908. Serial No. 414,639.

To all whom it may concern:

Be it known that I, THOMAS H. SYMINGTON, a citizen of the United States of America, residing at the city of Baltimore, State of Maryland, have invented certain new and useful Improvements in Journal-Boxes, of which the following is a specification.

The present invention relates to a journal box, and more particularly to a closing means, or lid for such box.

The lid to be described is of the "lift-off" variety, so called for the reason that in opening, it lifts free of the box. Though my invention has been shown in connection with this type of lid, certain of its features may be otherwise utilized.

The members which coöperate to hold the lid in closed position are a projecting lip on the box, a coöperating hook on the lid, and a spring by which the hook and lip are maintained in engagement. By arrangement of these elements as hereinafter set forth, the spring is caused to press the lid into close engagement with the mouth of the opening, whereby a permanent and tight closure is effected and maintained, so that dust and grit cannot enter. The cover though tightly secured is easily removed.

The device is simple and durable, may be manufactured at low cost and does not easily get out of order.

Referring to the accompanying drawings: Figure 1, is a vertical, longitudinal cross-section of the box and cover; Fig. 2, is a perspective of the cover, detached; Fig. 3, is a fragmentary view looking from the left in Fig. 1 of the lower part of this box with the cover detached.

There is shown a box 1 of a well-known type having an opening 2 for the insertion of lubricant and packing material. Bordering the opening there is below a horizontal lip 3, and above a horizontal lip 4 having an upright extension or flange 5 with a vertical inwardly disposed surface 6; the upper surface of the lip 4 is curved from its forward edge 7, upward and backward to the vertical surface 6; laterally the opening is inclosed by vertical side lips 8 and 9. The outer edge of the lower lip and the two side lips and the top edge of the upper lip form a seat for the journal box lid. The lower portion of this seat is plane and inclined slightly inward from the vertical. The up-

per portion of the seat is curved inward through an arc of about 90°, till it intersects the inwardly disposed vertical surface 6 of the upper flanged lip 4. Looking at the seat in elevation from the front or rear of the car, it will be noted that it is inclined toward the vertical plane 6, coöperating therewith to form a wedge.

The journal box lid is constructed to conform to the seat and is provided on three sides, those corresponding to the upper and lateral lips of the box with a flange 11, turned at right angles to the adjacent surface. This flange is adapted to take over and inclose the corresponding lips and rest against the lateral face of each lip, which is disposed away from the opening; the upper flange of the lid, with the upper curved portion thereof forms a hook and presses with its inner face against the vertical surface 6. At its lower edge the lid is provided with an inwardly extending horizontal abutment 14, the edge of which 15 is turned up to form a socket for a spiral compression spring 16, the end 17 of which is passed through an opening 18 of the cover and turned at right angles. The spring 16 is interposed between the abutment 14 of the cover and the lower surface of the horizontal lip 9 and is maintained in engagement with the lip by means of a depending lug 19. The lower surface of the box is provided with a bracket 20 supporting an upwardly disposed rest 21 and the lower edge of the cover near the middle point thereof is provided with a notched extension 22. Near the upper extremity of the cover is a suitable handle 23.

In the operation of the device, the lid is rested on the seat and the spring brought into engagement with the lower surface of the horizontal lip 3, the upper spirals inclosing the depending lug 19; the lid is then pressed inward against the seat, its top flange sliding over the curved surface of the upper lip 4, whereby the lid is given an upward tendency and the spring is compressed. When the flange 11 passes the vertical surface 15, the lid is depressed by the spring until its inner surface rests on the seat, the flange engaging the vertical surface 6. The tension of the spring presses the lid into engagement with the wedge formed by the seat and the vertical surface 6, whereby a tight closure is maintained.

To remove the lid, a bar is placed with its

extremity on the rest 21, and brought into engagement with the notch 22, at the lower extremity of the lid. Upward pressure of the bar lifts the lid against the tension of the spring, whereby the upper flange at the hook is released from the flanged lip and by manual engagement of the handle 23, the lid may be removed.

Having thus described my invention what 10 I claim and desire to secure by Letters Patent is:

1. A journal box having an opening, a lip on one side of the opening and an abutment on the other side of the opening, a lid flanged to inclose the box adjacent the opening and having means on one side for engaging the lip an abutment on the other side externally placed in regard to the abutment of the box and a compression spring between 20 the abutments.

2. A journal box having an opening, a lip on one side of the opening, an abutment on the other side of the opening, a lid flanged to inclose the lips of the opening and having 25 a hook on one side for engaging the lip and an abutment on the other side, externally placed in regard to the abutment on the box, and a compression spring between the abutments engaging both abutments and secured 30 to one abutment only.

3. A journal box having an opening, a lip on one side of the opening, an abutment on the other side of the opening, a lid flanged

to inclose the lips of the opening and having a hook on one side for engaging the lip and 35 an abutment on the other side, externally placed in regard to the abutment on the box, and a compression spring between the abutments secured to the abutment on the lid.

4. A journal box having an opening, a lip 40 on one side of the opening, an abutment on the other side of the opening, a lid flanged to inclose the lips of the opening and having on one side a hook for engaging the lip, and an abutment on the other side, externally 45 placed in regard to the abutment on the box, and a lug on one abutment encircled by the end helix of the spring to center the latter and maintain it in alinement.

5. A journal box having an opening, a lip 50 on one side of the opening, an abutment on the other side of the opening, a lid flanged to inclose the lips of the opening and having a hook on one side for engaging the lip, and an abutment on the other side, externally 55 placed in regard to the abutment on the box, a seat on the lid adjacent the abutment, a bar to coöperate with the seat whereby the spring may be compressed to release the lid, and a rest on the box to receive the end of 60 the bar and act as a fulcrum.

Signed by me at Baltimore, Maryland.

THOMAS H. SYMINGTON.
